United States Patent Office

Des. 178,259
Patented July 10, 1956

178,259

MILK BOTTLE

James I. North, Baltimore, Md.

Application August 5, 1955, Serial No. 37,334

Term of patent 14 years

(Cl. D58—6)

*Fig. 6.*Fig. 1 is a side elevation view of a milk bottle, showing my new design;

Fig. 2 is a top plan view thereof;

Fig. 3 is a bottom plan view thereof;

Fig. 4 is a cross-sectional view thereof taken on the line 4—4 of Fig. 1;

Fig. 5 is a cross-sectional view thereof taken along the line 5—5 of Fig. 2; and

Fig. 6 is a perspective view thereof, taken on an enlarged scale.

What is claimed is:

The ornamental design for a milk bottle, as shown.
